FOOT EXERCISER

Charles E. M. Murphy, Bellerose, N. Y.

Application January 13, 1950, Serial No. 138,449

7 Claims. (CL. 128—57)

1

My invention relates to an exercising device and more particularly to a foot and leg exerciser. Heretofore it has been proposed to provide foot exercisers having a rotatable roller constructed and arranged to be rotated by movement of the user's foot thereover. It has also been suggested to use a single roller or plurality of rollers, rotatably mounted upon a suitable support, whereby the foot may be exercised and massaged by moving the foot transversely of the rollers or between the surfaces of successive rollers.

While the above referred to types of foot exercising and/or massaging devices no doubt function for their intended purposes, they are open to certain objections which are inherent in their basic design and construction. Exercisers comprising a single roller designed for free rolling movement on the floor are objectionable for the reason that, in use of the device, it is difficult to maintain a fixed path of rolling movement, and there is also a tendency for the roller to slip from beneath the foot of the user, particularly at the extreme limits of travel of the roller across the floor. In exercising devices of the character wherein a plurality of rollers are rotatably mounted upon a base or other support, the rollers are restrained against outward movement from beneath the user's foot; however, exercising movement with respect to an individual roller is confined to a rather limited path. In other words, since the axes of the rollers are positioned in the supporting base in substantially fixed planes, the change in angularity of the foot and the leg of the user is restricted during forward and backward movement of the foot across the peripheral surface of the roller.

After considerable research and experimentation, I have found that improved results can be obtained by constructing and arranging the roller and its supporting base whereby the height of the roller and its effective distance from the user may be simultaneously varied. There are many advantages which accrue by reason of such design. For example, it will be readily appreciated that provision for adjustment of the roller, as above mentioned, permits a wide range of change of angularity of the foot and of the leg during the exercising operation, which is particularly beneficial to the muscles of these members. In some instances, the need for exercise of the leg muscles is predominately indicated, in which case the device can be quickly and easily adjusted to a position to afford variable flexing and/or stretching of the muscles of the leg, as desired. By means of my improved arrange-

ment, economies in manufacture are effected, not possible with devices involving a plurality of rollers, since a single roller adjustable as to height from the base support and in effective distance from the user, eliminates the necessity of having a number of rollers mounted at specifically different heights from the base.

An object of my invention is to provide an improved foot and leg exerciser.

Another object of my invention is to provide an improved exerciser adapted for massaging the foot, and exercising the foot and leg muscles.

Yet another object of my invention is to provide an improved exerciser, including a rotatable element, constructed and arranged whereby the height of said element with respect to its support may be quickly and easily adjusted.

Still another object of my invention is to provide an improved exerciser having a rotatable element adapted to be positioned at spaced intervals on its support, through an arc of substantially 180°, whereby the height of the element above the base of its support is varied.

Yet still another object of my invention is to provide an improved exerciser, including a revolvable element, having means whereby the resistance to rotation of the rotatable element may be varied.

A further object of my invention is to provide an improved foot and leg exerciser constructed and arranged whereby the height of the rotatable element and its effective distance from the user may be simultaneously varied.

A still further object of my invention is to provide an improved exerciser, that is strong and sturdy in construction, consisting of but few parts, and not liable to get out of order even after long and continued use.

The above and other desirable features of novelty and advantage of the present invention will be more clearly understood by reference to the attached drawings illustrating a preferred embodiment of the invention.

In the drawings:

Figure 1 is a perspective view of the exercising device of the present invention;

Fig. 2 is a sectional view along line 2—2 of Fig. 1; and

Fig. 3 is a perspective view of a modified form of exerciser.

Referring to the drawings, and more particularly to Fig. 1, the exerciser comprises a base structure designated generally by numeral 1, a pair of arcuate shaped roller support members 2, and a foot engaging roller 3. The base includes

foot members 4, which may be formed integral with members 2, and end pieces 5, secured to said members by means of screws 6 or other suitable fastening means. It will be noted that each foot member 4 is formed with a stepped portion 7, constructed and arranged inwardly from the ends of members 2, whereby to provide firm supports at the corners of the device. Each of the roller support members is provided with a slot 8, formed in the inner face 9 of the member, said slot being defined by upper and lower walls 10 and 11, respectively, and a bottom wall 12 (Fig. 2). As will be seen in Fig. 1, the lower wall 11 of the slot is formed with a plurality of recesses 13, at spaced intervals of its peripheral portion, to provide seats for the end portions of the shaft of the roller 3, as will be described more fully herein-after.

Reference being had to Figs. 1 and 2, the roller 3, which is preferably formed from rubber or other resilient material, comprises a central foot engaging portion 14 terminating in conical shaped flared ends 15, and a metal shaft 16, to which the rubber body of the roller is secured, as by vulcanizing. It will be observed that the shaft 16 is of length approximately equal to the horizontal distance between the bottom walls 12 of the slots 8, and that the end portions 17 of the shaft seat in opposite recesses 13 of the slot. The roller is adapted to be rotated by moving a foot across the central portion 14, and in order to increase the frictional contact between the foot and the roller, the surface of its foot engaging portion is formed with undulations 18.

The roller is normally freely rotatable when the end portions of the shaft are seated in opposite recess; however, its rotative resistance may be varied by means of a brake device comprising a fibre pin or block 19, positioned in an aperture 20, formed in an arm 21 of a bifurcated member 22. The lower end of the pin is adapted for bearing engagement with portion 23 of the shaft, the degree of pressure between the bearing surfaces being controlled by means of an adjustable set-screw 24, threadable into the aperture above the pin. In connection with the construction of the bifurcated member 22, it will be noted that arm 21 thereof over-hangs the outer face of member 2, and accordingly, the member is embraced by the arms 21 and 21'. By reason of this arrangement, movement of the roller is restrained to the arcuate path determined by the curvature of members 2. In other words, when it is desired to move the roller from seated position in one pair of recesses to another pair, the end portions of the shaft are brought into registry with the slot 8, and the roller is then pushed in the direction of the pair of slots in which it is to rotate, movement of the shaft from the normal horizontal position being prevented by the arms 21 and 21'.

In using the exerciser, it is placed on the floor with one end facing the operator, who is seated in a chair, located so that the roller, when in the position shown in Fig. 1, is within easy reach of the operator's foot. The operator then imparts an oscillatory rotary motion to the roller by moving the foot backwards and forwards across the central foot engaging portion. In the first position of the roller, it is contemplated that very little stretching of the leg muscles will be required, to impart oscillatory movement, as above described. After a period of exercising in the first position, the roller is then moved to the next set of recesses where the exercising is continued, and so on, until the roller reaches the

limit of its travel along the support members 2. In each successive position of the roller, assuming that the distance between the operator and the front end of the exerciser remains substantially constant, the leg must be extended to obtain rotative contact between the foot and the roller. The rotative resistance of the roller may be quickly and easily varied as desired, at any exercising stage, by manipulating the set-screw associated with the brake device.

With reference to the arcuate shaped roller support members, it will be noted that when the roller is moved from one pair of recesses to the next adjacent pair, the height of the roller above the plane of the base structure, and its distance from the center of the base are simultaneously varied. By means of this construction desired exercising of the leg muscles is obtained, for the reason that different operative positions of the roller require that the operator raise or lower the leg, and simultaneously extend or retract the same, depending upon the direction in which the roller is being moved along the slot, in order to impart an oscillatory rotary movement to the roller.

Concerning the construction of the exerciser, it is preferably formed from metal or a metal alloy, however; it may be made of wood or other suitable material. In order to retain the exerciser in desired operative position, that is, to prevent it from sliding away from the operator when the rotative resistance of the roller is increased, the end of the exerciser may be placed against a suitable support, and to provide additional frictional contact with the floor, the feet may be provided with rubber gripping surfaces, not shown. In connection with the design of the recesses, in which the end portions of the roller seat, it will be noted that they are angularly disposed with respect to the lower wall of the slot, in a fashion calculated to permit easy seating or removal of the shaft from any set of recesses.

Referring to Fig. 3, there is shown a modified form of exerciser, comprising a base structure 25, a pair of similar arcuate shaped roller support members 26, and a foot engaging roller 27. The base includes end pieces 28, side pieces 29 and foot members 30. Each of the roller supports 26 is formed with a plurality of recesses 31, providing seats for the end portions of the roller shaft 16', said end portions being retained in seated position by means of springs 32 attached to links 33 and 34. The links 33 are pivotally mounted on members 26 by means of pins 35, or other suitable fastening means positioned on the vertical center lines of the members, and links 35 are apertured to receive the ends of the roller shaft, as shown. Rotative resistance of the foot engaging roller may be varied by means of a thumb nut 36, threadable on the end of the roller shaft.

The modified exerciser is operated in substantially the same fashion as is the preferred form of Fig. 1. When it is desired to shift the position of the roller 27 from one set of opposite recesses to the next adjacent pair, the roller is lifted from seated position, either manually or by using the toes, and pushing the roller along the upper edges of members 26, until the end portions of the shaft drop into the recesses. In each of the above described embodiments of the present invention, the recesses adapted to receive the roller shaft, are spaced at intervals of approximately 30° of the arcuate members.

While I have shown and described the preferred embodiment of my invention, I wish it to be under-

stood that I do not confine myself to the precise details of construction herein set forth by way of illustration, as it is apparent that many changes and variations may be made therein, by those skilled in the art, without departing from the spirit of the invention, or exceeding the scope of the appended claims.

What is claimed is:

1. An exerciser of the character described, comprising a base structure, a pair of spaced parallel coaxial roller support members secured to the base, a foot engaging roller, including a shaft having free end portions, and means associated with said support members adapted for selective engagement with the free end portions of the roller shaft, whereby to vary the height of the roller vertically of the plane of the base, and means associated with the roller to vary its rotative resistance.

2. An exerciser of the character described, comprising a base structure, a pair of coaxial arcuate shaped roller supported members secured to opposite sides of the base, each of said members having a plurality of recesses formed therein at spaced intervals in the vicinity of its arcuate peripheral position, a foot engaging roller, and means associated with the roller adapted to be selectively seated in opposite recesses of said supports, whereby to vary the height of the roller vertically of the plane of the base, and means associated with the roller to vary its rotative resistance.

3. An exerciser of the character described, comprising a base structure, a pair of similar coaxial arcuate shaped roller support members secured to opposite sides of the base, each of said support members having a plurality of recesses formed therein at spaced intervals in the vicinity of its arcuate peripheral portion, a foot engaging roller, including a shaft having free end portions, the free end portions of the shaft being adapted to be selectively seated in opposite peripheral recesses of the supports, whereby to vary the height of the roller vertically of the base, and means associated with the roller to vary its rotative resistance.

4. An exerciser of the character described, comprising a base, a pair of similar coaxial arcuate shaped roller support members attached to opposite sides of the base, each of said members having a slot formed in the vicinity of its peripheral portion, said slot having a plurality of recesses formed in one wall at spaced intervals thereof, and a foot engaging roller, including a shaft having free end portions, the free end portions of the shaft being adapted to be selectively seated in opposite recesses of the slots, whereby to simultaneously vary the height of the roller vertically of the base and its distance horizontally lengthwise from the center of the base.

5. An exerciser of the character described, com-

prising a base, a pair of similar coaxial arcuate shaped roller support members attached to opposite sides of the base, each of said members having a slot formed in the vicinity of its peripheral portion, said slot having a plurality of recesses formed in one wall at spaced intervals thereof, a foot engaging roller, including a shaft having free ends, said roller having an undulating resilient contact surface, the free ends of the shaft being adapted to be selectively seated in opposite recesses of the slots, whereby to simultaneously vary the height of the roller, vertically of the base and its distance horizontally lengthwise from the center of the base, and means to vary the rotative resistance of the roller.

6. An exerciser of the character described, comprising a base, a pair of similar coaxial arcuate shaped roller support members attached to opposite sides of the base, each of said support members having a plurality of recesses formed therein at intervals of 30° along the peripheral arcuate portion, a roller, including a shaft having free end portions, the free end portions of the shaft being adapted to be selectively seated in opposite peripheral recesses of the supports, whereby to simultaneously vary the height of the roller vertically of the base and its distance horizontally from the center of the base, means to urge the end portions of the roller shaft into seated engagement with the recesses, and means associated with the roller to vary its rotative resistance.

7. An exerciser of the character described, comprising a base, a pair of similar coaxial arcuate shaped roller support members attached to opposite sides of the base, each of said support members having a plurality of recesses formed therein at intervals of 30° in the vicinity of the peripheral arcuate portion, a foot engaging roller, said roller having an undulating resilient contact surface, means associated with the roller adapted to be selectively seated in opposite recesses of the supports, whereby to vary the height of the roller vertically of the plane of the base, and means to vary the rotative resistance of the roller.
